OSCILLATION SYSTEM

Richard H. Seaman, Los Angeles, and Carl A. Schwenden, Alhambra, Calif.

Application May 18, 1936, Serial No. 80,462

10 Claims. (Cl. 250—36)

Our invention relates broadly to electron tube oscillator systems and more particularly to a novel type of electron tube oscillator characterized by the condition wherein the filament cathode has a higher dynamic potential than the plate element in the electron tube.

One of the objects of our invention is to provide a type of electron tube oscillating system in which the tube oscillations are very persistent.

Another object of our invention is to provide a circuit network connected in such a way to a thermionic tube as to have the plate element in the tube dynamically at a low potential and the hot cathode at a higher potential.

A further object of our invention is to provide means for connecting the plate, the grid, and the filament of a thermionic tube to selected portions of associated circuit elements whereby the circuit is maintained in a state of oscillation, even though the load condition is changed over a wide range.

Still another object of our invention is to provide means for connecting a thermionic tube in such relation to associated circuit elements as to obtain a frequency of oscillation considerably higher than that which would be obtained if customary tube circuits were employed.

A further object of our invention is to provide an arrangement of inductive and capacitive elements in an oscillatory circuit embodying an electron tube, whereby the filament element in the tube may be connected in the dynamic, oscillating circuit at a potential higher than the dynamic potential on the plate element in the tube; the filament being energized by a dynamically balanced, separate source of power.

Still another object of our invention is to provide a push-pull arrangement in an oscillatory circuit operating in accordance with the fundamental characteristics of our invention.

A still further object of our invention is to provide a cascade arrangement of an oscillator tube and an amplifier tube, in which the filament element in each tube is maintained dynamically at a higher potential than the respective plate element.

Other and further objects of our invention reside in the elements and circuit arrangements hereinafter more fully described, with reference to the accompanying drawings, in which:

Figure 1 is a schematic diagram of the oscillator circuit of our invention; Fig. 2 shows a modification of the arrangement indicated in Fig. 1, and is especially suitable for very high

frequency work; Fig. 3 is a schematic diagram of a push-pull arrangement of the oscillator system of our invention; Fig. 4 shows a push-pull arrangement of modified form more suitable for high frequency work; Fig. 5 is a schematic diagram of an arrangement which is more powerful, and more adaptable to very high frequency work; and Fig. 6 is a schematic diagram of a circuit utilizing two tubes in cascade in order to obtain increased power out-put from the oscillator.

Referring to Fig. 1, reference character 1 denotes a customary three-element tube having a filament 2, grid 3, and plate 4. Reference character 15 denotes a grid leak resistance, and 14 a grid condenser, the combination providing a bias potential for the grid 3. Reference characters 12 and 13 denote high frequency by-pass condensers. A "B" battery for supplying power in the plate circuit is indicated at 11. Reference character 16 denotes a ground. A tuning condenser by means of which the frequency of the oscillating system can be adjusted to desired values is indicated at 9. The most significant feature of the circuit arrangement consists of the coils 5 and 6, which are exactly alike and wound together as a single coil. They are shown separately only in order to avoid confusion in circuit connections. As the condensers 12 bypass high frequency currents, the coils 5 and 6 may be considered, as far as high frequency currents are concerned, as being, in effect only one coil. The by-pass condensers 12 have the purpose of avoiding a short circuit on the "A" battery 10 supplying the power to the filament 2. If the battery 10 is replaced by the output of a low frequency source for supplying the filament power, by-pass condensers 12 must be chosen such as to form an open circuit to the low frequency power supply. Contacts 7 and 8 on coils 5 and 6, respectively, connect to the ends of the filament 2.

In the circuit of Fig. 1, as in all the circuits illustrated, the dynamic oscillating circuit includes the circuit from the grid to the parallel radio frequency paths comprising the twin coils 5 and 6 and the by-pass condensers 12, the connections to the filament from the twin coils, and the plate circuit through the condenser 13, as well as the interelectrode paths within the tube. The sources of power 10 and 11 do not enter substantially into dynamic oscillatory circuits but supply the power and the static potentials to the filament and plate elements.

Thus, as far as dynamic oscillations are con-

cerned, plate 4 is at the lowest potential while the filament is at a high potential. This is an essential difference between customary tube circuits and the circuit of our invention. With 5 contact 7 at point 37 in the circuit, the corresponding end of the filament would be at a low dynamic potential, while if contact 7 was connected at the point 36, the corresponding end of the filament would be at the highest available 10 dynamic potential with respect to the potential on the plate 4. It will be noted that with the connection shown, the grid and filament both are dynamically at a high potential with respect to the plate.

15 As mentioned before, coils 5 and 6 are wound closely together and act as a single coil. The oscillator, at first sight, may, therefore, seem similar to the Hartley oscillator, but this is not the case as is evident from the explanation just 20 given. In our experiments we have found the following great advantages in the oscillator system of our invention: The circuit oscillations are very persistent, that is, the circuit practically will not stop from oscillating no matter how it is 25 loaded or adjusted as to frequency, and the like.

We have also discovered that the frequency of 30 oscillation is considerably higher than with customary types of oscillators. In our experiments we have set up, for instance, a circuit as shown 35 in Fig. 1, and a Hartley oscillator circuit in which actually only one coil is used across the variable condenser, and in which the plate is dynamically at a high potential with respect to the filament. The condenser was exactly the same in both 40 circuits, and the plate-grid coil in the Hartley circuit was identically the same as our combined coil 5, 6, shown in Fig. 1. The result was that the Hartley oscillator generated frequencies corresponding to a wave length of about 20 meters, while our circuit shown in Fig. 1 generated a frequency corresponding to a wave length in the neighborhood of about 9 meters. Hence, we can see that with such a network, we have great 45 advantages in the ultra-high frequency band over customary oscillators, in addition to the advantage that more persistent oscillations, with more power, can be produced.

Fig. 2 is a modification of the circuit shown in Fig. 1. We have omitted the variable condenser 50 9 shown in Fig. 1 which connects essentially across the grid and the plate and serves the purpose of decreasing and adjusting the frequency of the generated oscillations. With this condenser 9 omitted in Fig. 2 powerful oscillations 55 at ultra-high frequencies can be produced which are considerably higher in frequency than oscillations produced in customary tube oscillators. It will be noted that a "C" battery 17 replaces the 60 automatic grid bias provided by condenser 14 and resistance 15 of Fig. 1. In Fig. 2, reference characters 5 and 6 denote again the two coils which are wound closely together and separated at the 65 respective ends, for direct current supply, by means of the high frequency by-pass condensers 12. Contact points 7 and 8 again serve the purpose of supplying a suitable high dynamic potential to the respective filament ends, with respect to the low dynamic potential of the plate 4. The 70 grid 3 is again, dynamically at a high potential, while the filament 2 also is relatively at a high dynamic potential with respect to the potential of the plate 4. Reference character 16 again denotes a ground which is connected to the plate terminus of the coil 5.

75 Fig. 5 is another modification of the circuit

shown in Fig. 1. The electron tube 1 contains a filament 2, a grid 3, and a plate 4, as in Fig. 1. The grid-plate condenser 9', is variable for the sake of adjusting the frequency of the generated oscillations. For very high frequency work, this 5 condenser may be omitted. Reference characters 5 and 6 denote the characteristic duplex coil of our invention, and it will be noted that the end 36 of coil 5 is disconnected from the remainder of the circuit. Coils 5 and 6 are again wound 10 closely together and are exactly alike. Contact points 7 and 8 are connected at suitable points on coils 5 and 6, respectively, in order to provide the corresponding filament with a potential dynamically at a higher level than the low dynamic 15 potential of the plate 4. A condenser for bypassing high frequency currents is represented at 13, and reference characters 10 and 11 designate the "A" and "B" batteries respectively. It will be noticed that neither an automatic nor a 20 battery source of grid bias is employed. We have found that with such a network as in Fig. 5, most persistent and powerful oscillations are obtained.

Fig. 3 gives a push-pull arrangement of our 25 new type of oscillator. Reference characters 5 and 6 indicate the twin coils which are wound closely together. High frequency by-pass condensers are shown at 12 and 13, and reference character 16 denotes a ground, as in Figs. 1 and 2, 30 the ground 16 in Fig. 3 being connected at the middle of coil 5. The automatic grid bias is provided, as in Fig. 1, by means of a grid leak resistance 15 and a grid condenser 14, for the grid 21 in tube 18, and by resistance 15' and condenser 35 14' for the grid 21' in tube 19. The variable condenser 9' across the respective grids of tubes 18 and 19 serves again the purpose of adjusting to a desired frequency. Condenser 9' may be omitted for very high frequency work. The filaments 40 20 and 20' of tubes 18 and 19, respectively, are energized by means of a single source, 10; and the source 11 supplies the power to the plate branches 45 of tubes 18 and 19 which includes the plate elements 22 and 22', respectively. Both power supplies 10 and 11 can be contained in a customary power pack; or source 11 can be replaced by a "B" eliminator, and source 10 by the secondary of a low frequency power supply transformer. If the filament is to be energized by a low frequency 50 current, the condensers 12 have to be chosen such that they form practically an open circuit for the low frequency currents, but essentially a short circuit for the generated high frequency current.

Contacts 7 and 8, which connect to filament 55 20, as well as contacts 23 and 24, which connect with filament 20', are adjusted to suitable points along the twin coils 5 and 6 so that the respective filaments 20 and 20' of the two push-pull tubes 18 and 19 are dynamically at a high potential with respect to the low potential of the respective plates 22 and 22' of tubes 18 and 19. It will be noted also that the two grids 21 and 21' are dynamically at a high potential. Push-pull oscillators of this type combine all the features and advantages brought out in connection with the explanation of Fig. 1, in addition to the features inherent to all push-pull oscillators—the latter being very well known in the 65 art.

Examining the circuit arrangement of Fig. 3 closer, will bring out the essential difference between customary tube oscillators and the novel oscillator of our invention. We note, for instance, that the plates are connected together, 70 75

that means, that they are dynamically as well as statically one unit while the filaments are dynamically two separate essential elements. They have, in our novel type of oscillator, functions like the plates in customary tube oscillators, because the filaments in our novel type of oscillator are dynamically at a high potential. The two grids also have to be separate, because they too are dynamically at high potentials.

Inasmuch as the oscillator of our invention, according to the explanation just given, has inverse actions in comparison to standard tube oscillators, a modified push-pull circuit arrangement employing a single tube of unique description has been devised and is shown in Fig. 4. The single tube 25 embodies two filaments 26 and 27, two grids 28 and 29, and only one plate 30, and will produce customary push-pull actions. For the sake of simplicity and clearness, we have shown direct current power supplies in Fig. 4. Reference character 10 denotes the source of power for the filaments 26 and 27, which are connected through contacts 7 and 8, and 23 and 24, respectively. The source for the plate supply is shown at 11, and separate sources for producing desired grid biases are indicated at 31 and 31'. Condensers 12 and 13 operate to bypass high frequency currents. The twin coils 5 and 6 are exactly alike, as before, and are wound closely together.

The contacts 7 and 23, and 8 and 24, connected along the respective coils 5 and 6, are adjusted so that the corresponding filament potentials are higher than the low dynamic potential on plate 30. The dynamic potential on plate 30 is supplied through the tap 38 on coil 5, tap 38 being held at ground potential by connection to the ground 16. A variable condenser can be connected between the two grids 28 and 29 in order to decrease and adjust the oscillator frequency. With such an arrangement as that shown in Fig. 4, most persistent oscillations at a greatly increased frequency can be produced.

Fig. 6 shows another novel arrangement of our invention wherein an additional tube 32 is employed as an amplifier in cascade with the oscillator tube 1. For the sake of simplicity, tube 1 with the filament 2, grid 3, and plate 4, and tube 32, with the filament 33, grid 34, and plate 35, are customary three-element tubes. Condensers 14 and 14" and resistors 15 and 15" supply, in the particular circuit shown, the proper bias potentials for the grids 3 and 34. These potentials can, of course, also be produced with customary "C" batteries. The grid condenser 14 and grid leak resistance 15 of tube 1 may be omitted in order to produce the effects brought out in connection with the explanations of Fig. 5.

Fig. 6 shows the twin coils 5 and 6, which are exactly alike and wound closely together, connected in circuit with tube 1. An additional pair of coils 39 and 40, which are also exactly alike and wound closely together, is employed in connection with tube 32. Coil 41, inductively coupled with coils 39 and 40, is the output coil of the oscillator system. Condensers 12 and 13, as usual, are connected as high frequency by-pass condensers and additional by-pass condensers 12' are employed in connection with the twin coils 39 and 40. Battery 10 supplies the power to the respective filaments 2 and 33, and source 11 supplies the power to the circuit connected in common to plate 4 and plate 35. Contacts 7 and 8 on coils 5 and 6, respectively, as

well as contacts 43 and 44 on coils 39 and 40, respectively, are for adjusting the filament potentials with respect to the dynamic potential of plates 4 and 35. The two-tube arrangement shown in Fig. 6 is, in principle, nothing more than a single tube oscillator of the type shown in Fig. 1 and utilizing tube 1, in combination with an amplifier employing tube 32, thus giving increased power output with the great persistency of oscillation which characterizes the oscillator of our invention.

It will be noted that the filament 2, by means of contacts 7 and 8 on the twin coils 5 and 6, is again dynamically at a high potential with respect to the dynamic potential of plate 4, while the grid 3 also is dynamically at a high potential. That is, the tube oscillator utilizing tube 1 has essentially the features brought out in connection with Fig. 1. The amplifier arrangement shown in Fig. 6 to the right of tube 1 and utilizing tube 32, also has the filament dynamically at a comparatively high potential, since contacts 43 and 44 are set close to the right hand or high dynamic potential ends of the corresponding twin coils 39 and 40. The grid 34 of tube 32 is energized through contact 42 from a suitable point along coil 5 in the actual tube oscillator circuit. The contact 42 could also be connected at places along coil 6, since dynamically both coils are in multiple and act together. With the arrangement shown in Fig. 6, we can obtain greatly increased power output of very persistent oscillations, and increased frequencies of oscillation.

It will be understood that the oscillating systems herein disclosed are typical of many different circuits, in which electron tubes can be employed in such a way as to have the plate dynamically at lower potential than the hot cathode as well as the grid. It is not intended, therefore, that our invention be limited to the particular embodiments shown, but only as defined in the accompanying claims.

What we claim as new and desire to secure by Letters Patent of the United States is as follows:

1. An electron tube oscillating circuit comprising an electron tube having plate, grid and filament electrodes, means for supplying a static potential to said plate electrode, parallel radio frequency paths connected between the plate and grid electrodes and constituted by a pair of inductances in intimate inductive relation, corresponding ends of said inductances being connected through radio frequency by-pass condensers, a source of filament current connected with said inductances, and means for connecting the terminals of said filament to selected corresponding points on said inductances intermediate the ends thereof, whereby said filament dynamically has a higher potential than said plate and a lower potential than said grid.

2. A push-pull electron tube oscillator system comprising a pair of three-electrode electron tubes and balanced circuits inter-connecting the electrodes of the respective tubes, plate, grid, and filament elements in each of said tubes, means for maintaining the plate elements in both said tubes dynamically at a low potential, means for maintaining the filament elements in said tubes dynamically at high potentials with respect to the corresponding plate elements, and means connected between the grid elements in said tubes for providing balanced radio frequency excitation for said grid elements, the dynamic potentials for said plate and filament elements be-

ing obtained by contact with the last said means intermediate the connections to said grid elements.

3. A push-pull electron tube oscillator system comprising an electron tube having a single plate element, a pair of filament elements and a grid element associated with each of said filament elements, means for maintaining said plate element dynamically at a low potential, means connected between said grid elements for providing balanced radio frequency excitation for said grid elements, said plate element being connected at the dynamic mid-point of said last mentioned means, said filament elements being connected 5 to said last mentioned means on either side of said mid-point connection, both terminals of each of said filament elements being given the same dynamic potential, whereby the filament elements are maintained dynamically at a higher 10 potential than said plate element.

4. An electron tube oscillating circuit comprising an electron tube having plate, grid and filament electrodes, means for supplying a static potential to said plate element, separate inductance elements disposed in circuit between the 15 plate and the grid electrodes to the opposite terminals of said filament electrode, and a source of filament current connected with said filament electrode through portions of said inductances, 20 said source being connected with one of said inductances at the connection thereof with said plate electrode and with the other of said inductances at the end remote from the connection thereof to said grid electrode, said inductances being arranged in intimate inductive 25 relation.

5. An electron tube oscillating circuit comprising an electron tube having plate, grid and filament electrodes, means for supplying a static potential to said plate element, separate inductance elements disposed in circuit between the 30 plate and the grid electrodes to the opposite terminals of said filament electrode, and a source of filament current connected with said filament electrode through portions of said inductances, 35

said source being connected with one of said inductances at the connection thereof with said plate electrode and with the other of said inductances at the end remote from the connection thereof to said grid electrode, said inductances being arranged in intimate inductive relation and having distributed capacity effective therebetween to provide substantially a single path for high frequency oscillatory currents, said inductances thereby being operative as a single 10 inductance in the generation of oscillation in said circuit.

6. An electron tube oscillating circuit as set forth in claim 1 and having a variable capacity element connected across said inductances for 15 varying the frequency of the generated oscillations.

7. An electron tube oscillating circuit as set forth in claim 5 and having a variable capacity element connected between the grid and plate 20 elements of said tube for varying the frequency of the generated oscillations.

8. An electron tube oscillating circuit as set forth in claim 1 and having means for supplying a bias potential for said grid element. 25

9. A push-pull electron tube oscillator system as defined in claim 2, and wherein the said means connected between the grid elements comprises a pair of inductances arranged in intimate inductive relation, and capacity elements connected 30 between corresponding ends of said inductances; a center-tap connection to one of said inductances providing the low dynamic potential for said plates, and connections to both said inductances at selected points providing the dynamic 35 potentials for said filaments.

10. A push-pull electron tube oscillator system as defined in claim 3, and wherein the said means connected between the grid elements comprises a pair of inductances arranged in intimate inductive relation, and capacity elements connected between corresponding ends of said inductances. 40
